(57) **CLAIM**

The ornamental design for a base for a display, as shown and described.

DESCRIPTION

FIG. 1 is a perspective view of a base for a display showing my new design;

FIG. 2 is another perspective view thereof;

FIG. 3 is a front view thereof, the rear view being identical to the front view;

FIG. 4 is a left side view thereof, the right side view being a mirror image of the left side view;

FIG. 5 is a top view thereof;

FIG. 6 is a bottom view thereof;

FIG. 7 is a perspective view thereof showing the outer sleeve slid on the inner post;

FIG. 8 is a front view thereof showing the outer sleeve slid on the inner post; and,

FIG. 9 is a left side view thereof showing the outer sleeve slid on the inner post.

The broken line portions of the base for the display in all views represent unclaimed portions of the claimed design and form no part thereof.
